UNITED STATES PATENT OFFICE.

JOSEPH A. GROEBLI, OF NEW YORK, N. Y., ASSIGNOR, BY MESNE ASSIGNMENTS, TO
ALPHONSE H. KURSHEEDT, OF NEW YORK, N. Y.

JACQUARD MECHANISM.

1,034,106.

Specification of Letters Patent. Patented July 30, 1912.

Original application filed March 9, 1910, Serial No. 548,240; Divided and this application filed November 17, 1910. Serial No. 592,758.

To all whom it may concern:

Be it known that I, JOSEPH A. GROEBLI, a citizen of the United States, and a resident of the city, county, and State of New York, have invented certain new and useful Improvements in Jacquard Mechanism, of which the following is a specification.

This case is a division of my application filed on the 9th day of March, 1910 and 10 serially numbered 548,240.

The present invention relates to improvements in jacquard mechanism, and in the present case I have illustrated only such parts of a complete jacquard mechanism as 15 is necessary to show the application of my invention, as a complete jacquard would necessitate a very extensive showing and my present invention can be readily understood from the present showing and from 20 cross reference to certain United States patents issued to me or to my assignee. Furthermore my invention is susceptible of use in different forms of jacquards.

The present invention is intended more 25 particularly for use in jacquards such as are used to operate embroidering machines, wherein a large tambour frame carries a fabric on which a multiplicity of needles operate to produce embroidery and which 30 tambour frame the jacquard automatically positions for each stitch. Certain U. S. patents have been issued to me or to my assignees, for jacquards for such purpose, the 35 patents being dated August 21, 1883 and November 6, 1894, and numbered 283,707 and 528,632, respectively, to which reference will be made herein. My present invention may be advantageously embodied in the structures of either of said patents as well as in 40 other jacquards and a reference to such patents will teach the present invention and its uses sufficiently to enable those skilled in the art to employ the present invention in other forms of jacquards.

45 Jacquards for operating embroidering machines are required to position the tambour frame as above stated and to be effective they must be capable of producing a great number of positions of the tambour frame

within certain limits, the greater the number of such positions which the jacquard is capable of controlling the greater the efficiency of the jacquard and the more perfect the product of the embroidering machine will be. The possibilities of the embroidering machine are increased as the number of positions which the jacquard can produce in the tambour frame are increased. The movement of the tambour frame during any given stitch is comparatively small, when it 50 is considered that such tambour frame is from 20 to 30 feet long and the machine proportionately large; and as the jacquard is automatically controlled by means of a jacquard card or paper roll, the movements 55 in the jacquard parts when initiated by the pattern roll are considerably greater than the ultimate movement produced on the tambour frame of the embroidering machine, and the movement is reduced by suitable mechanism before the tambour frame 60 is moved thereby. This movement in the jacquard when first produced is usually a variable reciprocating movement and is transformed into a variable rotary movement. In some jacquards, as in my said 65 second patent, two movements of different units are combined into a single final movement by mechanism which permits of a greater number of positions of the tambour 70 frame with few parts in the jacquard, by combining two movements of different units in various combinations. The present invention relates to that part of the jacquard 75 by which the variable reciprocating movement is transformed into a variable rotary movement and the present invention may be employed whether the jacquard is one in which the extent of movement is determined 80 by a single primary operation, or one in which two or more movements of different units are combined to produce a movement varying according to the number of combinations which it is possible to obtain with the 85 two movements. These broad objects are, to a certain extent, met in a former construction, that of my said second patent, but the present invention is an advance over 90 95

such device and others because I am enabled to convert a reciprocating movement of any extent, within the limits of the machine, into a corresponding rotary movement. In other words there is no limitation, as far as changing the character of the movement is concerned upon the number of different positions which can be obtained within the limits of the jacquard. Furthermore the change from a reciprocating into a rotary movement is accomplished by a positive and certain device, which will occasion no defects in the product of the embroidering machine and which will not throw greater stress upon the jacquard mechanism as a whole.

It is necessary in changing a reciprocating into a rotary movement to do so with a device which will return after each operation to its first or normal position before a repositioning; and the direction of movement must be susceptible of change at each operation, whereby the tambour frame will be moved, say first to the right and then to the left; and it must also be capable of moving the tambour frame successively a number of times in a given direction to increase the amplitude of movement of the tambour frame or for other purposes. In my said second patent the reciprocating movement is converted into a rotary movement by means of rack frames which actuate gears, the racks being oppositely disposed so as to be engaged singly on either side of the gear, whereby the direction of the rotary movement may be changed and though such device is positive and will permit of a variation in the extent of movement it has its limitations, because the teeth of the gear make it necessary for the racks to mesh with such teeth and the variations in the movement are thus limited. To do away with the teeth on the racks and gear would necessitate a very great pressure between the parts to produce enough friction to make the movement positive and such construction would not meet the requirements. In all former devices there has been a relative movement between the engaging and the engaged parts. That is, in my said second patent there is relative movement between the racks and the gear, while if the gear teeth were removed and smooth bars used instead of the racks, there would still be relative movement between the element engaging and the element engaged, in the transforming mechanism. I have therefore provided a converting device wherein I am able to provide sufficient gripping surface to make the operation positive and certain and wherein the elements gripping and the element gripped have no relative movement during the transforming operation.

I prefer to employ racks as before and

segments meshing therewith at all times, the segments forming part of a pair of arms or levers. Upon these levers I provide clutching elements either of which may be thrown into engagement with the element of the revolving mechanism, which, in the present showing is a drum or pulley mounted on a shaft. As the levers carry the clutching elements, the latter move with the element clutched so that there is no relative movement between the element clutching and the element clutched and the racks and segments can remain in mesh at all times. Since the clutching element can be engaged with the clutched element at any point any adjustment is possible within the extreme limitations of the machine.

In the drawing forming a part of this application, the figure is a plan view of the preferred form of my present invention.

I will first describe the mechanism herein shown and I will then show by reference to my other patents what application my present invention has in a complete jacquard.

In the present showing I have provided a supporting frame 1, which is suitably mounted in the jacquard structure and which supports various operating elements to which reference will be made.

The shaft 2, which carries a cam 3, is the main or operating shaft of the jacquard and from which the operating force of the jacquard is derived, as in my said previous jacquard structures. In the form of my invention herein shown the revolution of the cam 3 operates continuously to produce a rocking motion in the lever 4, which fulcrums at 5, through the connection of the bowl 6 on an ear of this lever, with the groove 10 of the cam 3. The link 7 which is fulcrumed by means of a pin 8 in the slot 9, of the lever 4, would, so far as the cam is concerned, be operated the same extent at each revolution of the cam, but in certain known forms of jacquards the pin 8 is moved to various positions along the lever 4, whereby the extent of movement imparted to the link 7 is adjusted to secure very fine differences of movement. This adjustment of the fulcrum is caused by mechanism controlled automatically from the jacquard card or roll and a description of the mechanism therefor would lead to a very extensive description; and the mechanism therefor is known in the art. The link 7, responding to the action of the lever 4 imparts a reciprocating movement to an element which operates either directly or indirectly in the transformation of the movement into a rotary movement and the element here shown operated by the link or pitman 7, is a frame 11 having side bars 12, 13, which are guided between the sides and bottom of the supporting frame 1, wherein

the frame 11 is movable longitudinally; and this frame is provided with part of the transforming mechanism.

Inasmuch as the frame 11 responds to the movement of the link 7 and inasmuch as the extent of movement is automatically controlled from the jacquard roll it will be apparent that the reciprocating movement of the frame 11 will be a variable one, depending upon the extent of movement which it is desired to produce upon the tambour frame, the automatic positioning of which is the primary function of the jacquard. The movement produced in the frame 11 is therefore a variable reciprocating movement.

The function of the frame 11 is to provide the operating force which is transformed into a rotary movement by which the tambour frame positioning elements are operated; and this reciprocating movement is much greater than the final movement required to position the tambour frame, which latter is usually not more than a fraction of an inch at one operation. In the present showing there is no combining of two different movements into a single movement in the jacquard proper, for the purpose of reaching a greater number of ultimate movements with a few parts, although the primary movement is reduced before acting upon the tambour frame positioning elements; but cross reference will be made hereinafter to my former patents showing how the present mechanism may be employed in a jacquard wherein two movements of different units are combined to produce a great number of ultimate movements.

As herein stated the extent of the reciprocating movement is altered by changing the fulcrum of the link 7 on the lever 4, which is the principle on which certain jacquard mechanisms are based. But the variable reciprocating movement may be produced by connecting, say the link 7, with the bar M of my said earlier Patent 283,707. In that event the reciprocating movement of the bar M depends upon which of the many jacquard slides engages the lever O and these jacquard slides are actuated automatically by the jacquard card or pattern roll.

The shaft 16 in the present showing is the element which is operated by the reciprocating movement, whereby the transformation of the movement takes place, and this shaft corresponds in function say with the shafts D², D⁴, of my said second patent and it may be similar in every respect, except in the manner of revolving it, and the entire jacquard mechanism beyond this shaft, that is, every element succeeding this in the mechanical operation may be the same as in my said second patent. It also corresponds with the shafts G and H of my

said first patent. Instead of revolving this shaft by means of the rack and gear in the manner shown in my previous patent I have employed a device susceptible of any adjustment within the extreme limits of the machine.

The mechanism by which the reciprocating elements cause the operation of the revolving elements is very simple and positive and the band shown in my parent application may be dispensed with. The shaft 16, 70 which is the element on which the reciprocating mechanism operates forms the fulcrum point of two levers 14, 15, which are journaled loosely on the shaft and are disposed in opposite directions. The arm or 80 lever 14 is provided with a toothed segment 18 which meshes with the rack 19 of the bar 13 forming part of the reciprocating frame 11; while the lever 15 has a similar toothed segment 20 which meshes with 85 the rack 21 of bar 12 of the frame 11 and both segments are in mesh with their respective racks at all times. Each lever carries a clutching element adapted to operate on the drum 17 carried by the shaft 16. 90 On the lever 14 is a lever 22 which fulcrums at 26 and its engaging end 23 is preferably serrated at 24 to produce sufficient friction when engaged with the drum to prevent slipping and the engaging surface may be 95 great enough to insure proper gripping. The other end 27 of the lever is engaged by a segmental plate 28 carried by a sliding plate 38 and the engaging surface of the part 28 is struck on an arc centering in 100 the shaft 16. A spring 25 is connected with the end of the lever 22 and with the lever 14 and tends to pull the end 23 into engagement with the drum 17. The lever 15 is similarly provided with a clutching lever 105 30 having the clutching end 31 pulled toward the drum 17 by a spring 33; and the lever 30 fulcrums from the point 29 and has an end 34 which is engaged by the segmental plate 35 on the plate 38. The levers 14 and 15 are reversely disposed. The segmental plates 28 and 35 are so disposed that either of the levers 14, 15, may be engaged with the drum 17 but not both at the same time.

From the description thus far it has been shown how the operating force is derived and how the extent of movement is controlled. Another important factor is the device for determining the direction of 120 movement when it is converted into a rotary movement. I prefer to employ a device for this which will apply the power therefor through certain elements and to initiate such by means of other elements, the latter 125 being also controlled from the jacquard card. The plate 38 is adapted to be reciprocated in its longitudinal direction and the

means for operating it is adapted to produce any one of three different positions. In one the right clutch will be thrown into engagement with the drum 17; in another the left one in and the right one out; and in the third both clutches out, for the return of the reciprocating frame.

The plate 38 corresponds in operation with the plate L^a in my said second patent and the mechanism for operating it may be the same. The frame 11 is reciprocated at each revolution of the main shaft 2 through the cam 3, the lever 4, and the link 7 and the reciprocation of this frame causes the levers 14 and 15 to revolve about the shaft 16 in directions opposite to each other and the extent of movement of these levers will depend upon the extent of movement of the frame 11, which will vary according to the control of the jacquard card. The machine is shown in the drawing in the starting position with the plate 38 in its intermediate position. In such position the clutches 14 and 15 are held out of engagement with the drum 17. If, now, the next stitching operation requires that the shaft 16 be revolved to the right, then the rod 53 will have been positioned by the jacquard card, in the position shown in the drawings, when the slot 45 of the arm 42 will engage the pin 51 of the lever 48. The next movement of the rod 50 longitudinally will rock the lever 47 which is secured on the shaft 49 and this will rock the lever 42, 43. As the latter is fulcrumed at 44 to the plate 38 the latter will be reciprocated in the guiding flanges 39, to the left. This will cause the segmental part 35 to rock the lever 30 away from the drum and the movement of the segmental part 28 will permit the clutching lever 22 to be drawn by its spring 25 into engagement with the drum. The plate 38 will remain in its lefthand position, when the frame 11 is drawn by the link 7 and in consequence of the rocking of the lever 14 by the rack 19 and segment 18 the drum 17 and its shaft 16 will be revolved to the right, the extent of movement of which will depend upon the extent of movement of the frame 11. When the frame 11 completes its forward movement the rod 50 will be reversed in its direction and as a result the lever 47 will rock the shaft 49 and the lever 42, 43, back to an intermediate position as in my said second patent. This will rock both clutching levers 14 and 15 into a disengaging position, free of the drum 17. The direction of movement of the frame 11 is now reversed and since neither clutching lever engages the drum the return movement of the frame 11 will be an idle one, leaving the shaft 18 where it was placed by the forward movement of the frame 11. If the next movement of the shaft 16 is to be in

the same direction the above operation is 65 repeated; but should it be necessary to move the shaft 16 to the left, then the rod 53 is operated by the jacquard card to move the lever 42, 43, in a direction reverse to the first operation and this will bring the recess 46 of the arm 43 into engagement with the pin 52 on lever 48. The movement of the rod 50 will now rock the shaft 49, through the lever 47 in a direction reverse to that first described and the plate 38 will 70 be moved to the right. This will carry the clutching lever 22 away from the drum and the end 31 of the other clutching lever 30 will be permitted to be moved by its spring into engagement with the drum. The forward movement of the frame 11 will now cause the shaft 16 to be rotated to the left and the extent of rotation will again depend upon the extent of reciprocation of the frame 11. Upon the completion of the forward 75 reciprocation the plate 38 will be moved to its intermediate position, both clutches will be thrown out and the return movement of the frame 11 will not alter the position of the shaft 16. In this manner a variable 80 reciprocating movement is transformed into a variable rotary movement. The fact that the clutching levers move with the drum when revolving the latter and the fact that there may be sufficient engaging surface, 85 avoids any liability of slipping between the clutching and clutched elements during the transforming operation.

The device thus far described is duplicated as many times as may be necessary 100 for the particular jacquard mechanism to which it is applied. Where a single initial movement is produced by the changing fulcrum method, or by the lever engaging various slides as in my said first patent there 105 will be two such devices as has been described; and they are preferably superimposed. When two movements of different units are united to produce a single ultimate movement in the jacquard proper as 110 hereinbefore mentioned and as shown in my said second patent then four sets of transforming devices as herein shown will be used. As the combining of the two sets of movements takes place beyond the transforming devices the mechanism from the latter through to the tambour frame may be 115 the same as in said patent.

Various changes may be made in the construction without departing from the spirit 120 and scope of my invention.

Having described my invention what I claim is;

A jacquard mechanism embodying reciprocating means adapted to be operated varying 125 extents, and having racks, rotative mechanism including a shaft, oscillatory elements fulcrumed on said shaft and provided

with toothed sectors meshing with the racks of said reciprocating means, whereby the oscillatory elements will be operated in different directions and according to the extent of the operations of said reciprocating means, clutching levers moving with said oscillatory elements, each adapted to clutch a portion of the rotative mechanism, whereby the latter will be operated by the reciprocating means, springs tending to move the clutching levers into operative relation with the rotative mechanism and jacquard card controlled means for controlling the clutch levers, embodying a reciprocating member having plates for moving said levers and 15 curved in the arc of their movement.

Signed at the city, county and State of New York, this 14th day of November, 1910.
